UNITED STATES PATENT OFFICE.

ALONZO EDWARD LEWIS, OF INGERSOLL, ONTARIO, CANADA.

CUSHION-HEEL.

1,099,609.

Specification of Letters Patent.

Patented June 9, 1914.

Application filed October 24, 1913. Serial No. 797,090.

To all whom it may concern:

Be it known that I, ALONZO EDWARD LEWIS, a subject of the King of Great Britain, residing at Ingersoll, in the Province 5 of Ontario, Dominion of Canada, have invented new and useful Improvements in Cushion-Heels, of which the following is a specification.

My invention relates to an improved 10 form of spring heel and has as its principal object the provision of a form of heel construction for shoes which shall be relatively cheap and durable and yet be of moderate cost and easily manufactured.

15 A further object of my invention resides in the particular arrangement and combination of parts hereinafter described.

In the accompanying drawing:—Figure 20 1 is a central sectional view through the heel portion of a shoe, made according to my invention. Fig. 2 is a top plan view of the view shown in Fig. 1. Fig. 3 is a perspective view of a cork pad which may be substituted for the spring shown in Fig. 1.

25 Throughout the separate views the same part is designated by the same reference character.

Referring more particularly to the drawing, 1 designates the upper of a shoe 30 provided with an inner sole 2 and an outer sole 3. Within the heel portion of the shoe is a thin heel casing 4 which is made the same shape as the heel and covers the lower portion of the upper on the inside and extends 35 downwardly forming a hollow space 5 below the portion of the insole which is adapted to support the heel of the wearer. Forwardly of the space 5, the casing 4 is inserted between the sole and, insole as indicated at 6 and all three members, the sole, 40 insole and casing are connected together by a rivet 7.

On the outside of the upper 1 is a leather heel cap 8 which extends down below the 45 lower edge of the upper and incases the heel casing 4 on the outside, surrounding the space 5. It will be seen that the cap 8 extends across the bottom of the heel and on the outside of the heel and the bottom is a 50 leather pad 9. It will be seen also that the pad 9, cap 8 and bottom portion of the casing 4 are joined together by rivets or other

means such as pins, the members 4 and 8 also being joined together by rivets such as 11.

55

Within the space 5 is a spring 12, one end of which is fastened to a metal plate 13 which is riveted to the bottom of the heel member 4 by means of rivets such as 14. The upper end of the spring 12 is connected 60 to a plate 15 which is similar to the plate 13 and which bears against the under face of the insole 2 where it extends above the space 5. It will be seen that the spring 12 is connected to the plates 13 and 15 by 65 means of integral extensions such as 16 which project from the edges of the plates and which are coiled over so as to embrace the portion of the spring lying adjacent the plates. It should be noted also that the 70 heel cap 8, the upper 1 and the upper edge of the casing 4 are fastened together by means of rivets 17. It will be understood also that if desired, additional padding may be placed within the casing 4 to protect the 75 foot of the wearer, but such protection being an obvious matter, it is not shown in the drawing.

Referring more particularly to Fig. 3, I have shown therein a cork pad 18 which 80 may be substituted for the spring 12 in the form shown in Fig. 1.

Having thus described my invention, what I claim is:—

1. A shoe comprising in combination, a 85 hollow heel structure including a steel casing, an insole extended above the base of said heel structure, said casing being extended at one end thereof in contact with said insole and being riveted thereto, and 90 a leather heel cap covering the outer surface of said casing.

2. A shoe comprising in combination, a hollow metal heel, an outer leather cap covering the lower part of the upper and the 95 sides and lower surfaces of said hollow metal heel, and a leather pad on the bottom of said metal heel.

In testimony whereof I affix my signature in the presence of two witnesses.

ALONZO EDWARD LEWIS.
